TELEVISION FILM PROJECTOR

Harry R. Lubcke, Los Angeles, Willet H. Brown, Santa Anita, and William S. Klein, Los Angeles, Calif., assignors to Don Lee Broadcasting System, Los Angeles, Calif., a corporation of California

Application July 27, 1940, Serial No. 347,906

17 Claims. (Cl. 178—7.2)

This invention relates to television transmission from motion picture film, and particularly to methods and apparatus for accomplishing such transmissions when the frame rate of the film differs from that used in the television transmission.

The present standard motion picture film is projected at a rate of twenty-four frames per second. The most widely used standard of television transmission (the R. M. A. standard) utilizes a repetition frequency of thirty per second with a two to one interlace, so that the picture field is scanned every sixtieth of a second, with the result that whatever the phase relationship may be between the motion picture projector and the television pickup, a change of frame of the film will occur during certain of the television scansions if the ordinary type of motion picture projector be used. The time required for moving the film between successive frames is about 14% of the frame period, which equals about $\frac{1}{72}$ of a second or 35% of one television scanning period. It will thus be seen that with the standard motion picture projector the frame of the film will be changed every two and one-half scansions, resulting in a darkening of the field which lasts for about one-third (35%) of the scansion.

The present invention is concerned with the storage type of television pickup tube, typified by the "Iconoscope," wherein the signal generated by the scansion of each point of the picture field is proportional (to a first approximation) to the integral of the light which has fallen on that point since it last was scanned. If the field has been dark a portion of the time since the last scansion the intensity of the signal will be reduced approximately in proportion to the ratio of the time of darkening to the total time between scansions.

The field at a television receiver is illuminated only one point at a time, each point being illuminated once in each $\frac{1}{30}$ of a second under present standards, and this rate is itself slow enough to result in a perceptible flicker. It is to avoid this flicker that "interlace" is used, alternate lines being scanned in successive scansions, for it has been found that if the rate of flicker of the field as a whole is doubled it becomes imperceptible, the inter-line flicker not being noticed and the eye appreciating only an apparent average illumination. If, however, the intensity of signal differs materially for the successive scansions, as it will if the field has been darkened for film changing before one scansion but not before the

next in the same repetition period, the value of the interlace is largely lost, and a flicker of a particularly annoying type results.

In the past the problem thus presented has been met in two distinct ways each involving the use of a special type of projector. The first of these methods involves displaying successive frames of the film for unequal intervals, the first frame being exposed during three scansions of the field, while the succeeding frame is exposed during two scansions only, thus retaining the same average film speed but making the change of frame occur each time in the same epoch of the scanning. The field is illuminated briefly between the scansions, which take place while the photosensitive screen is dark.

The second method of solving the problem involves the use of a continuous projector, wherein the film progresses at a constant rate through the projector and the consequent motion of the image is optically compensated so as to hold it in a fixed position on the screen. This method can be used either with the storage type or the instantaneous type of television pickup, but the projector is expensive, complicated, and must be manufactured with an extremely high degree of accuracy in order to be satisfactory.

The method of our invention, as above stated, involves the use of a television pickup or camera of the storage type, and among the objects of the invention to provide a method of transmitting motion pictures by television which is applicable to any desired ratio of film frame rate to scanning rate; to provide a method to which standard motion picture projectors may be readily adapted; to provide a method which will produce flickerless television images irrespective of the frame and scansion rates employed; and to provide a method which greatly decreases the cost and complexity of the equipment used. It is also an object to provide apparatus whereby the method here set forth may be accomplished, and to provide apparatus with which direct pickup cameras may be used for motion picture projection with no positional or electrical inversion of the camera.

Our invention possesses numerous other objects and features of advantage, some of which, together with the foregoing, will be set forth in the following description of specific apparatus embodying and utilizing our novel method. It is therefore to be understood that our method is applicable to other apparatus, and that we do not limit ourselves, in any way, to the apparatus of the present application, as we may adopt vari-

ous other apparatus embodiments, utilizing the method, within the scope of the appended claims.

The instant invention operates through the cooperation of two groups of factors. The first group is dependent upon the nature of vision as it affects the perception of flicker, and in such perception contrast is a primary factor. Flicker (i. e., visible or apparent flicker), is increased if the variation in intensity of one point from instant to instant is high. It is also increased if the area which is flickering is in immediate proximity to an area which is not, or which is flickering in opposite phase. Sharp definition of the flickering area therefore increases its apparent intensity.

The second group of factors has to do with the operating characteristics of storage type television pickup tubes. These tubes will operate over a definite range of operating conditions. When an optical image is focused upon the sensitive mosaic of the tube the individual droplets or "islands" of photosensitive material lose electrons, in the initial instant of illumination, proportionally to the illumination, thereby acquiring positive charges. As these charges increase with time the more highly illuminated portions (and therefore the more positive portions) exhibit space charge effects to a greater and greater extent, as a result of which the emission decreases, so that they approach a certain limit of potential. Added to this is the fact that the more positive points attract more strongly any stray electrons which may be in the neighborhood, and this also has the effect of decreasing with time the rate at which these points acquire positive charges. The photosensitive mosaic is scanned by a moving beam or pencil of electrons, which has a twofold effect. First, certain of these electrons neutralize the positive charges which were photoelectrically acquired. Second, there is also a tendency of the scanning beam to knock off secondary electrons, which causes the particles to tend to swing positive rather than negative, the magnitude of these effects being dependent upon the velocity and intensity of the impacting beam and the potential of the electrodes which pick up the electrons knocked off or emitted by photoelectric action. The two effects cooperate to drive the various areas to a definite equilibrium. In practice it is usually the effort to have the scanning beam bring the points scanned to complete equilibrium.

It is an experimental fact, however, that the degree of neutralization of charge obtained in scanning is under the control of the operator, i. e., that it is possible by varying the intensity of the scanning beam to neutralize the stored charges more or less completely, leaving more or less of a residual charge having image characteristics upon the screen. Since it is the neutralization of charge that generates the television signal it would appear obvious that the best picture would be obtainable when the stored charge was completely neutralized. Again, however, it is an experimental fact that if the scanning beam be gradually increased in intensity from zero, the signal will be found to approach a maximum with the charge incompletely neutralized, and after this point is reached relatively large changes in intensity of the scanning beam cause relatively little change in signal intensity.

Another operating feature of these tubes is the fact that the degradation of the image due to the limitation of positive charges in the high lights is reduced by "back lighting"; i. e., if the

walls of the tubes are constantly illuminated from a source which does not illuminate the mosaic itself, the contrast of the transmitted image is increased. This is probably because the tube walls themselves almost inevitably acquire a certain amount of photoelectric coating, and back lighting causes this coating to emit electrons and thus acquire a positive charge, which helps to draw free electrons away from the mosaic and prevents the accumulation of a negative charge upon the walls, which would have an opposite effect.

Considered broadly, the method of our invention comprises projecting the motion picture 15 to be transmitted upon the screen of a storage type television pickup intermittently as with the conventional type of projector, scanning the screen with an electron beam preferably of minimum intensity so as to leave a material picture 20 charge upon the screen, and illuminating the screen during the period of occultation of the film by a diffused light which will reduce the contrast in average illumination between the portion of the picture area which is illuminated 25 for the full frame period and that which is scanned after a period of occultation. Preferably, also, the occultation is accomplished so as to cut off illumination gradually instead of suddenly, making the contrast between those portions which have been occulted and those which have not more gradual, and back lighting is also used to increase the effectiveness of the period during which the screen is fully illuminated by the image as will be more fully set forth later.

30 From the aspect of apparatus the invention comprises the combination with television pickup equipment of the storage type and a motion picture projector having an intermittent motion for progressing the film and a shutter for occulting this film during its progression, of means to supplying to the screen during occultation a general illumination distributed over the screen which will maintain the average illumination of the picture field sensibly constant.

35 Referring to the drawing:

Fig. 1 is a schematic diagram, reduced to lowest terms, showing the essential features of a system embodying our invention.

Fig. 2 is a graphical representation showing 50 the relationship existing between frame frequency, vertical scanning frequency, repetition frequency, and illumination in the system of our invention.

Fig. 3 is a graphical representation of the distribution of illumination over the picture field where conventional apparatus is used.

Figs. 4 and 5 are diagrammatic representations of two forms of shutters adapted for use with this invention.

60 Fig. 6 is a schematic showing of a modification of the apparatus shown in Fig. 1.

In the diagrammatic representation of Fig. 1 the film 1 is preferably standard sound-motion-picture film, exposed at the rate of twenty-four 65 frames per second and bearing upon its edge the customary sound track. The major portion of the projector may be in any conventional form, and is shown as including the usual feed reel 2 on which the film is stored before projection, and 70 from which it is unwound by means of the pull-down sprocket 3, to be progressed past the film gate 4 by a claw or other intermittent mechanism 5, and thence passed over the takeup sprocket 7 and through the sound head 9 to be rewound 75 upon the takeup reel 10. The various loops and

auxiliary sprockets which are utilized in the conventional projector are used here also, but are not shown since they are completely conventional and would merely complicate the showing.

The film is illuminated by an optical system comprising, for example, a lamp 11 backed up by a reflector 12, with a condensing lens 13 arranged in accordance with the usual practice to focus an image of the filament through the film gate 4 into the plane of the optical center of a projecting lens 14. Instead of the image being projected directly upon the screen, however, it is inverted deflected by a first surface mirror 15 through the shutter 17 and onto the inclined screen 19 of a storage type television pickup tube 20. The tube is enclosed within a conventional camera housing 21 which is indicated by the dash lines.

The television camera is entirely conventional and with it are associated the usual deflecting circuits, master pulse and scanning generators, etc., but these are not shown as they are well known to those skilled in the art and are merely ancillary to the present invention.

The primary difference between the setup thus described and the combination of a standard motion picture projector and a standard television camera lies in the shutter 17. A preferred form of this shutter is shown in Fig. 4. It differs from the standard shutter in its scimitar shape, the curved edges being provided to cause occultation of the image on the different portions of the screen at slightly different epochs, so that the transition band between occulted and non-occulted film will not occur in perfectly straight lines across the image and will therefore be less apparent to the eye. This is a secondary feature, however, since the important characteristic is that the shutter is translucent or light diffusing rather than either transparent or opaque. This may be accomplished by making the shutter of transparent plastic (e. g., "Lucite") and spraying upon it droplets of transparent plastic or lacquer, which, by forming minute lenses, alter the focal distance and diffuse the image so as to permit substantially the same amount of light to fall upon the sensitive plate 19 during the occultation period as between occultations, but destroy the image characteristics of the illumination.

The inverting mirror 15 is inserted in this system solely for the purpose of making the direct pickup camera immediately available for motion picture transmission without change other than removal of the regular direct pickup lens, whose place is taken by the projection lens 14. The mirror 15 reinverts the image from the upside down film, so that no switching or other manipulation is necessary in order to transmit upright pictures.

In considering the operation of the device attention first is directed to Fig. 2 which shows the time sequence of the various events in one half cycle of operation of a conventional projector as used with this type of television camera. The second half cycle differs from the first only in that the first scansion therein is of even instead of odd lines. Above the axis is shown the motion picture sequence, which starts with the operation of the pull-down mechanism, lasting 14% of the frame period, during which portion of the period the shutter occults the light from the film. With the ordinary, opaque type of shutter there is no illumination of the film for this occultation period and hence no storage of image on any part of the screen. At the end of

75 the pull-down time, the screen is fully illuminated and remains so until the next occultation and pull-down $\frac{1}{24}$ of a second later.

Beneath the axis line is shown the sequence of events in the television system. In this case the scanning of the field is assumed to have been completed at the instant that the pull-down starts, and during the first 8% of the scanning period the scanning beam moves from the lower right-hand corner of the picture field back to the upper left-hand corner of the field and then starts to scan the odd numbered lines of the picture field. When the odd lines have all been scanned the second scanning period begins, 8% thereof again being occupied by the return of the beam, and this time the even numbered lines are scanned.

If the scanning beam has been so adjusted as to neutralize the screen completely the effective charges start to build up from zero the instant the beam has passed, and continue to build up during the repetition or double scanning period. Because the field was dark during the first portion of this period, however, it is only when the double period has fully been accomplished after the pull-down that the elements are transmitted at full brilliancy. The relative rate at which any point in the field theoretically acquires its charge is proportional to the slope of curve 22, zero during occultation and constant between occultations, the actual rate being proportional also, of course, to the intensity of illumination of the individual point. The strength of the signals generated by the scanning of the point at any time t is similarly proportional to the integral of this slope between the limits $(t-r)$ and t , where r is the period of repetition, or $\frac{1}{30}$ of a second, the curve representing this integral being illustrated by the curve 23 of Fig. 2, 20 wherein the ordinate at any point representing an instant t is equal to the ordinate of curve 23 at the point t minus its ordinate at $(t-r)$.

If the successive sections of the curve 23 be superimposed, as shown in Fig. 3, it will be seen 25 that the average amount of light falling upon each part of the screen is the same when integrated over the complete half cycle of the two frames or five scanning periods, but that there are two areas, each occupying about 19% of the effective area of the frame (17½% of the total frame period including the return period) that increase in brightness 17½% every fifth scanning period, or twelve times per second, which causes the annoying flicker before mentioned. Between 30 these two areas of bad flicker there are transition areas, occupying the remainder of the television frame, in which the flicker changes phase, being reduced to half the intensity and increased to double the frequency half way between the two badly flickering areas.

When, now, the translucent or diffusing shutter of our invention is substituted for the opaque shutter of ordinary practice, the average illumination remains constant throughout and the visible flicker is greatly reduced. Some localized flicker remains. For those portions of the picture where illumination is equal to the average the flicker becomes zero, but the darker portions of the picture will now be increased in brightness during the intervals when they were formerly decreased, while in those portions which are above average brightness there will still be an increase in brilliancy, though of less magnitude, where the increase formerly occurred.

In each case, however, there are factors which

operate in addition to the fact that the actual intensity of the flicker has been reduced to about one-half in the case of the most widely varying points. In the case of the shadows these factors include first, the fact that apparent flicker is a function of brightness, and the less the intrinsic brilliancy the less the apparent flicker. The second is the fact that a short period of darkness occurring in a relatively long interval of illumination is very much less apparent than the reverse condition.

In the case of the high lights the favorable factor lies in the pickup tube rather than in the eye of the beholder, and resides in the fact that the charges in the high lights tend to approach a limiting value and that therefore a slight decrease in illumination during a portion of the scanning period has a very slight effect upon the strength of the signal where this limiting value is approached.

It should be borne in mind that the diffused illumination during the pull-down period covers the entire field and not any particular part of the field. Its effect therefore is merely to raise slightly the average illumination of the field as a whole, thereby slightly decreasing the contrast. This results only in a slight increase in the D. C. component of the signal, and since practically all television systems provide for some degree of manual background control, even where automatic control is also used, this can readily be compensated for.

While the factors thus far brought out comprise the major step in our invention, it may be made even more effective by further steps, each constituting a successive approximation toward the absolute elimination of flicker. The second major step in our method comprises the adjustment of the pickup tube so that the scanning beam is at minimum intensity consistent with approximately maximum signal, i. e., so that a residual image is left upon the screen after each scansion.

Why this should be so may not be apparent without a more detailed analysis than is practical here. Qualitatively, however, it may be seen that with the use of the system thus far described those portions of the field which formerly exhibited a flicker in brilliancy will now exhibit what may be termed a flicker in contrast, displaying the greatest amount of contrast in the course of those scancions which with the ordinary system would display the greatest degree of brilliancy. If we assume that one-third of the image strength is left when the area of greatest contrast is scanned, the next scanning of this area will result in a signal wherein two-thirds of the charge has been acquired at low contrast and one-third has been left at high contrast, thus increasing the differential of contrast of the low contrast scansion by one-third. Conversely, when the high contrast portion is next scanned only two-thirds of the charge will have been acquired at high contrast while the remainder has been acquired at low contrast, and the contrast upon this scansion will be correspondingly reduced. It will be understood that these figures are a first approximation only, and that the actual increases and decreases in contrast, result from the summation of a geometric series. The effect, however, is to tend to equalize the differences in contrast. It might be expected that this would result in "ghost" images in parts of the field where motion occurs, but actually residual flicker can be substantially neutralized before

ghosts become apparent. The third step in the series of approximations has already been mentioned, and comprises so occulting the field, as by means of the curved shutter blade, that the areas where flicker would normally occur are not marked out by clearly defined straight lines, which the eye can readily follow. That this actually has the effect of reducing apparent flicker is an empirical fact which will be left to the psychologists for explanation.

Since it will be apparent that the principal, and in fact the only undesirable effect of the system as thus far described is a slight reduction in contrast, it is desirable that the contrast be built up as much as possible, and we have found that the loss can be regained substantially in its entirety by the back lighting before referred to. This is accomplished by means of a lamp 25 mounted in the camera behind the screen of the pickup tube, where it will illuminate the walls of the tube without illuminating the screen itself.

It has been stated above that the illumination of the screen which is used in the elimination of the flicker is the average illumination of the picture field as a whole. A more accurate state-

ment would be that the illumination should be the average apparent illumination as determined by the eye. It will be recognized that the shutter 17 being of a diffusing character and also being a solid body, will have a different coefficient of refraction from the air in which it is operating, and there will be some loss of light due to reflection from its various surfaces, absorption in the passage through it, as well as by its defocusing effect. Experience has shown that this slight decrease in actual illumination below the average is not disadvantageous, in that the light which actually reaches the screen usually approaches more closely to the "ocular average" than where the absolute average illumination is the same.

Another method of practicing our invention, wherein the amount of flicker neutralizing light is under control, is to substitute for the shutter 17 of Fig. 4 the type shown in Fig. 5. In this case shutter 17' is also made of transparent material, preferably plastic, the shading upon the blade indicating a mirror deposit upon the surface which graduates in opacity and also in reflecting ability from the edges of the blade toward the center where the heaviest shading is shown, this portion being completely opaque. A lamp 27, backed by a reflector 29 and provided with a lens 30 throws a diffused beam of light along the path shown by the arrows against the reflecting surface of the shutter and thence onto the sensitive screen 19. The lamp 27 is shown as being excited by pure D.-C., indicated as supplied from a battery 31, since it is important that no flicker be present in this illumination, it being understood that any other pure D.-C. source may be substituted for the battery. Intensity of illumination may be adjusted by the rheostat 32. The graduated reflecting and occulting surface of the mirror 17' causes the diffuse reflected light from the lamp 30 to increase in intensity in substantially the same time and the same proportion that the image is decreased in intensity by the occulting action of the shutter. As in the case of the curved edges of the shutter blades shown in Fig. 4, the gradual occultation makes the transition from occultation to non-occultation and the reverse less distinctly marked, and thus contributes to the results desired. In this case the amount of flicker neutralizing light is under the control of the operator, who adjusts the rheo-

stat 32 until the best results are obtained as determined by eye upon a monitor screen.

Fig. 6 indicates a slight modification of the equipment shown at the right of Fig. 1. In this case the inverting mirror 15 is omitted, and the path of the image is direct from the lens 14 (Fig. 1) to the screen 19. In order that the light from the lamp 30' may reach the screen 19, the shutter 17a is mounted at an angle.

In Fig. 6 the pickup tube and the camera are inverted in comparison with the tube in Fig. 1, to indicate symbolically that in this case, since the image is not optically inverted, other means must be used in order that the transmission will appear upright.

Various other modifications of the mechanical means used to accomplish the method of this invention will be apparent. It is clear that a large part of the value of the invention may be appreciated even though the shutter 17 be made completely opaque throughout if its surface be reflecting. It will be further apparent that it is not necessary that the shutter control flicker neutralizing illumination, but that this may be done by using a lamp 30 having an instantaneous luminous response and opening and closing its circuit electrically in synchronism with the shutter. Other possible modifications will doubtless suggest themselves to those skilled in the art.

One of these possibilities deserves particular mention, however, and that is the total elimination of the shutter. The movement of the film in itself destroys the image, and tends to distribute the illumination uniformly over the screen. With certain types of picture, e. g., in pictures where the whole of one side of the field is materially different in illumination from the other, this method may give even better results than those heretofore discussed, since the average is taken for individual strips of the film, rather than for the whole. In other situations, however, it may result in streaks in the reproduced picture, and therefore it is not our present preference. The fact that it is usable at all, however, leads to the obvious conclusion that it is not essential that the shutter occult the image for the entire pull-down time and experiment has shown that this is the case, and that, if desired, the shutter which may be of any of the types here discussed, may be made to occult the image, for, say 10% instead of 14% of the pull-down time without introducing perceptible streaks or "travel ghosts."

It will also be apparent that the various modifications shown may be combined. Thus the shutter of Fig. 4 may be used and additional illumination supplied to the screen from the separate source 30, the non-specular reflection from such source onto the screen making up any deficiency in the average illumination caused by reflection from and absorption in the shutter of the light from the film.

In the final analysis we have found that so far as the eye can detect the method and apparatus as here described result in complete elimination of flicker. Examination of the screen under a magnifying glass reveals some residual flicker, just as the inter-line flicker can be thus detected even when direct pickup is used. For practical purposes, however, it is entirely satisfactory, and is not only simpler and less expensive than conventional methods, but is less difficult of adjustment, and being applicable to any ratio of frame frequency to scanning frequency, is more flexible.

We claim:

1. The method of television transmission from motion picture film with a pickup device having a photosensitive screen of the charge-storing type which comprises the steps of progressing said film intermittently, projecting stationary images of successive frames of said film onto said screen during substantially the whole intervals between such progressions, and illuminating said screen during the periods of movement of said film with substantially the same quantity of light as comprises said images but having different distribution over said screen than the light projected thereon during the image projecting intervals.
- 15 2. The method of television transmission from motion picture film with a pickup device having a photosensitive screen of the charge-storing type which comprises the steps of progressing said film intermittently, projecting stationary images of successive frames of said film onto said screen during substantially the whole intervals between said progressions, continuing to project illumination from said film onto said screen during the periods of progression, and destroying the image characteristics of said illumination during said periods.
- 20 3. The method of television transmission from motion picture film with a pickup device having a photosensitive screen of the charge-storing type which comprises the steps of progressing said film intermittently, projecting light through said film and onto said screen, focusing said light as an image of a portion of said film upon said screen during substantially the whole intervals between such progressions, gradually destroying said focus immediately before the period of progression of said film, and gradually restoring said focus at the end of said period.
- 25 4. The method of television transmission from motion picture film with a pickup device having a photosensitive screen of the charge-storing type which comprises the steps of progressing said film intermittently, projecting light through said film and onto said screen, focusing said light as an image of a portion of said film upon said screen during substantially the whole intervals between such progressions, gradually decreasing the intensity of said image immediately before the period of progression, and maintaining the total illumination of said film substantially constant by general illumination increasing in intensity as the intensity of said image decreases.
- 30 5. The method of television transmission from motion picture film with a pickup device having a photosensitive screen of the charge-storing type which comprises the steps of progressing said film intermittently, projecting stationary images of successive frames of said film onto said screen during substantially the whole intervals between such progressions, occulting said images at intervals, such occultation occurring non-rectilinearly across said screen and during the periods of progression of said film, and illuminating said screen generally during the periods of said occultation with a quantity of light substantially equal to that forming said images.
- 35 6. In the method as set forth in claim 1, the additional step of scanning said sensitive screen with an electron beam, said beam being of sufficient intensity to remove only partially the charges stored by the projection of light thereon.
- 40 7. In the method as set forth in claim 1, the step of occulting said images from said screen during said periods of progression, separately generating light during said periods, and illu-

minating said screen generally with said separately generated light during said periods.

8. The method as set forth in claim 1 including the step of illuminating separately the portions of said pickup device adjacent said screen while preventing said illumination from reaching said screen.

9. Television apparatus for the transmission of signals from motion picture film comprising a motion picture projector including means for intermittently progressing a film therethrough, means for illuminating said film during substantially the whole intervals between such progressions, a projection lens for forming an image of the illuminated portion of said film, and means for simultaneously destroying said image and for illuminating the plane thereof with substantially the same amount of light differently distributed during the periods of progression of said film.

10. Television apparatus for the transmission of signals from motion picture film comprising a motion picture projector including means for intermittently progressing a film therethrough, means for illuminating said film during substantially the whole intervals between such progressions, a pickup device of the charge-storing type, a projection lens for forming an image of the illuminated portion of said film upon the photo-sensitive screen of said pickup device, and a semi-transparent shutter timed with said intermittent means for destroying the image characteristics of the illumination from said projection lens reaching the plane of said image during the periods of progression of said film.

11. Television apparatus for the transmission of signals from motion picture film comprising a motion picture projector including means for intermittently progressing a film therethrough, means for illuminating said film during substantially the whole intervals between such progressions, a pickup device of the charge-storing type, a projection lens for forming an image of the illuminated portion of said film upon the photo-sensitive screen of said pickup device, and a shutter of transparent material having a light diffusing surface timed with said intermittent means for destroying the image characteristics of the illumination reaching the plane of said image during the periods of progression of said film.

12. Television apparatus for the transmission of signals from motion picture film comprising a motion picture projector including means for intermittently progressing a film therethrough, means for illuminating said film during substantially the whole intervals between such progressions, a projection lens for forming an image of the illuminated portion of said film, a shutter of transparent material and having a mirror surface of graduated opacity increasing from the edges of said shutter to the center thereof, said intermittent means occulting said image during the periods of progression of said film, a separate source of light, and means for directing light from said source onto said surface at an angle such as to be reflected therefrom onto the plane of said image.

13. Apparatus in accordance with claim 9 including means for inverting the image produced by said projection lens.

14. The combination as set forth in claim 9 including a shutter for occulting said image during the periods of progression of said film, a separate source of illumination, and means timed with said shutter for directing illumination from said source onto the plane of said image during the periods of occultation only.

15. In combination, a motion picture projector having intermittent means for progressing a film therethrough, means for illuminating a portion of said film during substantially the whole intervals between such progressions and a projecting lens for forming an image of said illuminated portion, a television pickup having a photo-sensitive screen of storage type positioned in the plane of said image, separate means for illuminating said pickup with the exception of said screen, and a shutter on said projector timed in synchronism with said intermittent means, said shutter being formed of transparent material and having a light diffusing surface.

16. Apparatus in accordance with claim 15 wherein said shutter comprises a rotating blade having non-radial edges.

17. Apparatus in accordance with claim 15 wherein said shutter comprises a rotating scimitar-shaped blade.
